UNITED STATES PATENT OFFICE.

FRANCIS H. RICHARDS, OF HARTFORD, CONNECTICUT.

FASTENING DEVICE.

No. 926,768.

Specification of Letters Patent.

Patented July 6, 1909.

Application filed June 7, 1901, Serial No. 63,516. Renewed July 19, 1905. Serial No. 270,437.

To all whom it may concern:

Be it known that I, FRANCIS H. RICHARDS, a citizen of the United States, residing at Hartford, in the county of Hartford and 5 State of Connecticut, have invented certain new and useful Improvements in Fastening Devices, of which the following is a specification.

This invention relates to devices for securing machine and kindred parts fixedly together, and is especially directed toward the furnishing of a fastening device for use in assembling shafts and parts carried thereon in machines where precision in the relative position of the secured parts is desired.

It is a further object of the invention to provide a fastening device adapted to be made in very small sizes with a high degree of precision, and also at a low cost of manufacture.

This invention constitutes an improvement upon a fastening device disclosed in my application Serial No. 37,420, filed November 23, 1900, in which there is shown, 25 described and claimed a device for securing machine parts together. The invention set forth in the application referred to embodies a locking piece or element of peculiar form and construction, and which, in the 30 organization therein shown and described, is seated in an opening extending longitudinally of the shaft to which the second member is attached, this opening being made partly in each of the two members secured 35 together. Ordinarily, therefore, as therein set forth, the opening for the reception of the locking piece extends lengthwise of the shaft, and the part of such opening in the latter terminates in a shoulder. In the 40 present improvement, however, the organization is such that the opening or recess in which the locking piece or element is seated extends transversely to that opening in the secured member in which the shaft is located when the parts are assembled. Thus 45 the present improvement provides a two-part fastening device of such a nature that both recesses or openings (that for the shaft and that for the locking piece) are adapted 50 to extend entirely across or through the respective parts, facilitating thereby the necessary machining or other treatment of the parts to fit them for their connection. The 55 present improvement also provides an opening for the reception of the locking piece or element, which is smooth and truly cylin-

drical as distinguished from the corresponding opening in my hereinbefore-mentioned device, in which the opening or cavity is shown as provided throughout with thread- 60 sections, although it will be understood that in the form of the connecting device shown in that application it is not essential that these thread-sections be all present.

In the drawing accompanying the present 65 specification, Figure 1 illustrates my present improvement as applied to the securing of a crank or arm to a shaft. Fig. 2 is an end elevation of the parts shown in Fig. 1, looking along the shaft. Fig. 3 is a sectional view 70 on the plane of the line 3—3 in Fig. 1. Fig. 4 is a longitudinal section of the crank or arm, the plane of the section corresponding to the axis of the opening in the arm through which the shaft is adapted to extend, and 75 this figure showing particularly the relation of the openings in the crank or arm, one for the reception of the shaft and the other for the reception of the locking piece or element. Fig. 5 is a section of the arm or crank shown 80 in the preceding figures, the plane of the section being that indicated by the line 5—5 in Fig. 4. Fig. 6 is an elevation of a portion of the shaft constituting one of the illustrated connected members, this figure showing the 85 shaft as removed from the arm and indicating the recess in the shaft in which the locking piece or element is adapted to fit. Fig. 7 is a section on the plane of the line 7—7 in Fig. 6. Fig. 8 is an elevational view of the 90 locking piece or element shown in Fig. 3, the same being removed from its assembled position.

Similar characters of reference designate 95 corresponding parts in all figures.

The fastening device of this invention, as of that disclosed in my hereinbefore-mentioned application, may be said to comprise cylindrical and conical surfaces so combined with relation to each other and to their respective coöperative surfaces that the reliability of the fastening device, considered as a whole, is independent of the particular position, within limits, in which the two parts or members are placed for the purpose 100 of being secured one to the other. The conical surface mentioned, coöperating with its opposed surface in the use of the device, results in a wedging or binding of the parts in place, while the aforesaid cylindrical surface is so disposed with reference to the other surfaces as to render an effective bind- 110

ing action to a considerable degree independent of the relative position of the parts one to the other.

Entering upon a more detailed description 5 of the embodiment of the invention illustrated, S designates a shaft and W a crank or arm secured together by means of a device embodying the present invention; these particular parts, it will be understood, are 10 chosen merely for illustrative purposes.

R designates a locking piece or element whose surfaces constitute, in the preferred form of the invention, the before-mentioned operative conical and cylindrical surfaces for 15 effecting the locking of the parts. These surfaces are combined in such a way that the locking piece or element is practically a cylindrical one. The conical surface, coöperating with a proper surface, effects the locking 20 of the parts by reason of the longitudinal movement of the locking piece or element. The reaction surface receives the lateral thrust due to the slight lateral movement of the locking piece when urged to position. 25 One or both of these surfaces is preferably spirally arranged upon the locking piece. They are here shown as both arranged in this manner. The cavity or opening, see 2, for the reception of the locking piece R extends 30 transversely to the axis of the shaft S and preferably entirely through the crank, arm or other part connected thereto, as the forming of a through opening in the arm, etc., will facilitate the making thereof. This opening 35 is a straight opening—that is, a bored or drilled opening—and, furthermore, it is not material whether the locking element fits snugly therein or not. Likewise the opening 3 in the arm for the reception of the shaft S, 40 and which, it will be noticed, extends transversely to the axis of the opening 2, need not necessarily be of a diameter requisite to form a snug fit of the shaft therein, as the effect of the locking piece when moved to its 45 locking position is to wedge the parts firmly together irrespective of the looseness of the parts.

The locking piece R, embodying the cylindrical and conical surfaces mentioned, is 50 shown as provided with a screw-thread 4 on its exterior surface; the diameter of this locking piece and the coarseness of the pitch of its thread or threads will be such as to insure ample strength to withstand the strain to 55 which the parts may be subjected. In the construction illustrated, the top surface of the thread 4 upon the locking piece R constitutes a portion of the surface of a cylinder; that is, the stock in which the thread is 60 formed is cylindrical from end to end. This surface at the top of the thread constitutes the mentioned cylindrical surface, designated for reference herein by 4^a. The core or body of the locking piece, however, tapers 65 from one end to the other, the thread in this

instance being deeper at the entering end of the screw than at the opposite end. The surface of this core; that is, the surface at the bottom of the thread, forms the mentioned conical surface, which is designated for reference herein by 4^b.

It is evident from the foregoing description that if the thread-sections upon one of the parts to be connected, and which serve to effect the longitudinal movement of the locking piece when the same is rotated, are made of a depth not less than the minimum depth of the thread on the locking piece R, nor greater than the maximum depth of such thread, that (the tops of) these thread-sections will bed against or contact with the conical surface 4^b at the bottom of the thread on the locking piece and as the latter is moved inward result in a slight lateral movement of the piece. Hence, owing to the tapering body of the locking piece, the lengthwise movement of this piece will be accompanied by its slight lateral movement. These mentioned thread-sections are, in the present instance, formed in the part opposite 90 to the arm or crank, see the thread-sections 5 formed in the surface of the concave recess 6 in the shaft S disposed in line with the bore of opening in the arm. The thrust arising from the lateral movement of the locking 95 piece R is taken by the opposite part—that is, the arm W, and preferably the surfaces between which this thrust or pressure is exerted are cylindrical so as not to render the reliability of the fastening device dependent 100 upon an exact position of the crank or arm with reference to the shaft. As before stated, the locking-piece R is of substantially uniform diameter from end to end of the thread, as measured across the top of the 105 thread, and to render the top surface only of this thread operative as a thrust surface the bore of the opening 2 in the arm or crank for the locking-piece may be cylindrical and is preferably unprovided with a thread or 110 thread-sections, permitting, thus, the top of the thread on the locking piece to impinge against its surface. Hence the operative contact, and by this expression I mean the contact to which the principle of the invention may be referred, is, in the present embodiment, upon one side, cylinder to cylinder, and upon the other a wedging or transverse action is present. It is not important, therefore, in assembling and reassembling 115 the parts that they should always be located in identically the same relative position to render the present fastening device effective as such, although by the use of this invention the parts may be secured one to the other 120 with great precision. This permissible variation in position with attendant uniformity in attachment is especially desirable in the securing of small machine parts one to the 125 other.

Having described my invention, I claim—

1. In a two-part fastening device, the combination with a locking piece having a cylindrical and a conical surface both spirally arranged, of a part having intersecting transverse openings with smooth bores, one for the reception of the part to be connected to the mentioned part, and the other for the locking piece, and the connected part, which has an operative surface spirally arranged.

2. In a two-part fastening device, the combination with a locking piece having a conical and a cylindrical surface diametrically opposite each other and at different distances from the center of the piece, of a part having intersecting transverse openings with smooth bores, one for the reception of the part to be connected to the mentioned part and the other for the locking piece, and the connected part having an operative surface spirally arranged.

3. In a two-part fastening device, the combination with a screw-like locking piece having cylindrical and tapering operative surfaces spirally arranged with respect to the axis of the screw, of a part having intersecting openings, one for the reception of the part to be connected to the mentioned part and the other for the locking piece, and the connected part, which has an operative surface spirally arranged.

4. In a two-part fastening device, the combination with a screw-like locking piece having cylindrical and tapering operative surfaces spirally arranged with respect to the axis of the screw, of a part having intersecting transverse openings, one for the reception of the part to be connected to the mentioned part and the other for the locking piece, and the connected part, which has an operative surface spirally arranged.

5. In a two-part fastening device, the combination with a screw-like locking piece having a greater depth of thread at the entering end of the screw than at the other end and also having one of its operative surfaces spirally arranged with respect to the axis of the screw, of a part having intersecting transverse openings, one for the reception of the part to be connected to the mentioned part, and the other for the locking piece, and the

connected part, which has an operative surface spirally arranged.

6. In a two-part fastening device, the combination with a screw-like locking piece having a greater depth of thread at the entering end of the screw than at the other end and also having one of its operative surfaces spirally arranged with respect to the axis of the screw, of a part having intersecting transverse openings with smooth cylindrical bores, one for the reception of the part to be connected to the mentioned part, and the other for the locking piece, and the connected part, which has an operative surface spirally arranged.

7. In a two-part fastening device, the combination with a locking piece, of a part to be connected having an operative surface spirally arranged, a part having intersecting transverse openings, one for the reception of the part to be connected to the mentioned part and the other for the locking piece, the contactual surface along one side of the locking piece being inclined to the axis of the locking piece, while the corresponding surface along the diametrically opposite side thereof in the same longitudinal zone is substantially parallel to said axis, and the two said contactual surfaces being disposed at relatively different distances from the axis of the locking piece.

8. In a two-part fastening device, the combination with a locking device, of a part to be connected having an operative surface spirally arranged, a part having intersecting transverse openings, one for the reception of the part to be connected to the mentioned part and the other for the locking piece, the contactual surface along one side of the locking piece being curved and inclined to the axis of the locking piece, while the corresponding surface along the diametrically opposite side thereof in the same longitudinal zone is cylindrical, and the two said contactual surfaces being disposed at relatively different distances from the axis of the locking piece.
